Leonard Reed

his ATTORNEY.

UNITED STATES PATENT OFFICE

ROLLIN B. POWERS, OF ASHLEY, OHIO

PRINTING DIE

Application filed December 23, 1932. Serial No. 648,621.

This invention relates to an embossing die and is designed more particularly for embossing data and designs on badges and the like by the method known as "hot stamping".

Heretofore embossing dies of this kind have been in one piece, the type being cut from the metal of the die block. Any change in the data or design made necessary the making of an entire new die. This involved a great deal of expense and was particularly objectionable where only minor changes were required, such as the date.

One object of the invention is to provide an embossing die having removable type which can be easily changed to enable the same die to be used for embossing a large number of different badges of the same general type.

A further object of the invention is to provide such a die in which either or both the main designation and the specific data may be changed.

A further object of the invention is to provide such a die in which the removable type members will be firmly held in position and accurately located.

Other objects of the invention will appear as the die is described in detail.

In the accompanying drawing Fig. 1 is a top plan view of an embossing die embodying my invention; Fig. 2 is a transverse sectional view taken on the line 2-2 of Fig. 1; and Fig. 3 is a horizontal sectional view of a portion of the die.

In the drawing I have illustrated one embodiment of my invention, which embodiment is designed primarily for hot stamping, but it will be understood that this particular embodiment has been chosen for the purpose of illustration only and that the invention may be embodied in dies for embossing or printing or for various similar operations and that the several parts of the die may take various forms, without departing from the spirit of the invention. The term "embossing" as herein used is intended to include any operation for impressing letters or designs on any material adapted to receive the same.

In the particular embodiment here illustrated the embossing die as a whole comprises

a die block having a central opening and consisting of a plurality of parts which are movable with relation one to the other to vary the size of the opening. Preferably the die block is rectangular in form and is here shown as square and divided into four separate parts 5 which are equal in size and are arranged edge to edge. The several parts of the die block have their inner portions or corners cut away and shaped to form the opening. In the present instance, the inner portions of the sections of the die block are arcuate in shape and when the die block is properly assembled they form a circular opening therethrough. As here shown, each section of the die block 65 has an upwardly extending flange 6 arranged about the inner edge thereof, the several flanges uniting to print a circular line on the badge. The die block may be supported and the several sections thereof held 70 in their assembled positions in any suitable manner. Usually it will be mounted in an ordinary type chase and secured therein by the usual clamping or locking devices, which are not here shown. Mounted in the opening in the die block is a center block 7 of a height approximately equal to the thickness of the type block and of a shape corresponding to the contour of the opening in the die block. 75 In the present instance, this center block is cylindrical. This center block may be provided with type or printing surfaces to emboss a main designation or design on the badge, such, for example, as the words "Horse show". This center type block is removable and may be changed when desired. 80 It is held in position during the embossing operation in the manner which will herein-after appear. The center block is of smaller size than the opening so that an annular space 85 is provided between the same and the wall of the opening and in this space type members 8 are arranged to emboss the specific data which is to appear on the badges, this data being here shown as comprising the words "State fair" and the year "1932". When the words or other data to be embossed are relatively short the remainder of the annular space may be occupied by slugs or spacing blocks 9 which are similar to the type mem- 90 95 100

bers except that they have no type faces and serve merely to retain the type members in their properly spaced positions. When the type members are to be inserted in the opening in the die block the several sections of the type block are loosened and moved outwardly slightly with relation to the center block so as to slightly increase the width of the annular space between the sections and the center block, thus permitting the easy insertion of the type members. However, the sections of the die block are retained in such positions that the type members will be supported thereby and may be easily located in the desired arrangement. When the type members have been fully assembled in the annular space the sections of the die block are moved inwardly by tightening down the locking devices of the chase, or otherwise, to clamp the type members between the sections and the center block. This tightening down of the die block sections not only clamps the type members between the sections and the center block but also firmly secures the center block to the die block.

The type members 8 are of the same radial width but they vary in thickness according to the letters which they bear. The outer vertical edges of one of the thicker type members will engage the circular wall of the opening in the die block along lines spaced apart a distance equal to the thickness of the type member and the central inner portion only of such type member will engage the cylindrical center block. Thus a relatively thick type member requires that the annular space between the center block and the die block shall be of a radial width slightly greater than the true width of the type member. The vertical edges of a relatively thin type member will engage the curved wall of the opening along lines spaced but a short distance apart and will have an effective width less than the effective width of the thicker die blocks. Consequently, if the type members are confined between circular metal surfaces the thicker type members will so limit the inward movement of the sections of the die block that the thinner type members will not be firmly clamped but will drop out of place when the die is lifted. To enable type members of all thicknesses to be firmly clamped in position I have interposed strips of compressible material between the type members and the die block, as shown at 10, and between the type members and the center block, as shown at 11, so that when the die block sections are tightened down this material will yield and accommodate itself to the surfaces of the type members and all type members will be firmly gripped thereby. The outer vertical edges of the type members will be pressed into this yieldable material while the inner vertical surfaces of the type members will flatten the adjacent portions of the yieldable material

so that each type member will contact with the yieldable material throughout the width of its inner surface. Consequently the type members are held firmly in position.

When embossing dies of this kind are used for hot stamping they are heated to a high temperature and the compressible material is therefore preferably of heat resisting material, such as asbestos. In addition to its functions in correctly positioning the type and retaining the same in place this compressible material will also yield to compensate for the expansion and contraction of the parts of the die under the influence of heat, thereby preventing any injury to the die or its supporting device due to the expansion of the several parts of the die.

It will be apparent that this die may be used for embossing a great variety of data and designs on different badges. In order to change the data it is only necessary to loosen the sections of the die block and make such changes in the type members as may be desired. In many cases this may involve only the changing of one type member of the date. However, if desired, all the data in the annular space may be changed and the central designation may be changed by removing the center block and substituting a different block therefor. For example, the same State Fair might be using the same style of badge for a horse show and for a cattle show but all the badges could be embossed from one die by simply changing the center type block.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In an embossing die, a die block having an opening therein and comprising a plurality of relatively movable parts, a center block arranged within said opening and spaced from the wall thereof, the parts of said die block being movable toward and from said center block and a plurality of removable type members arranged in the space between said center block and the wall of said opening, and adapted to be clamped therein by the inward movement of the parts of said die block.

2. In an embossing die, a die block comprising a plurality of parts having their inner portions shaped to form a circular opening in said die block when said parts are in engagement one with the other, a cylindrical type block arranged in said opening, said type block being of a diameter substantially less than the diameter of said opening, and a plurality of removable type members arranged between said type block and the wall of said opening, the several parts of said die

- block being movable toward said type block to clamp said type members between the type block and the die block.
3. In an embossing die, a rectangular die block divided into four substantially equal sections, said sections having their inner corners cut away to form an opening through said die block, a center block arranged in said opening, shaped to conform to the contour of the wall of said opening and spaced from said wall, and a plurality of removable type members arranged between said center block and the wall of said opening, the several sections of said die block being movable with relation to said center block to permit the insertion of said type members and to then clamp said type members between said center block and the respective sections of said die block. 70
- 20 4. In an embossing die, a die block having an opening therein and comprising a plurality of relatively movable parts, a center block arranged in said opening and spaced from the wall thereof, a plurality of removable type members clamped between said center block and said die block, and compressible material interposed between said type members and said die block. 80
- 25 5. In an embossing die, a die block having an opening therein and comprising a plurality of relatively movable parts, a center block arranged in said opening and spaced from the wall thereof, a plurality of removable type members clamped between said center block and said die block, and compressible material interposed between said type members and said center block. 85
- 30 6. In an embossing die, a rectangular die block divided into four substantially equal sections, said sections having their inner corners cut away to form a circular opening through said die block when said sections are in engagement one with the other, a cylindrical center block arranged in said opening and spaced from the wall thereof, a plurality of removable type members arranged between said center block and the wall of said opening, the several sections of said die block being movable with relation to said center block to permit the insertion of said type members and to then clamp said mem- 90
- 35 7. In an embossing die, a die block comprising a plurality of parts having their inner portions shaped to form a circular opening in said die block when said parts are in engagement one with the other, a cylindrical type block arranged in said opening, said type block being of a diameter substantially less than the diameter of said opening, and a plurality of removable type members 95
- 40 clamped between said type block and the sections of said die block, the several sections of said die block having upwardly extending flanges arranged to emboss a circular line about the impression taken from said die members. 100
- 45 8. In an embossing die, a die block having an opening therein and divided into a plurality of relatively movable parts along lines intersecting said opening, a center block separate from said die block, arranged in said opening and spaced from the wall thereof, and a plurality of removable type members arranged in the space between said center block and the wall of said opening, the several elements of said die being so arranged that they may be rigidly clamped one to the other by inward pressure on the parts of said die block. 105
- 50 9. In an embossing die, a die block having an opening therein and divided into a plurality of relatively movable parts along lines intersecting said opening, a center block separate from said die block, arranged in said opening and spaced from the wall thereof, and a plurality of removable type members arranged in the space between said center block and the wall of said opening, and a strip of compressible material interposed between said type members and the wall of said opening, the several elements of said die being so arranged that they may be rigidly clamped one to the other by inward pressure on the parts of said die block. 110
- 55 In testimony whereof, I affix my signature hereto. 115
